DOSING MECHANISM

Lucien Pierce, Malden, Mass.

Original application March 18, 1938, Serial No. 196,689. Divided and this application August 30, 1939, Serial No. 292,669

4 Claims. (Cl. 221—104)

This invention relates to dosing mechanism for use with comminuted material. While it may be used for measuring out predetermined quantities of any dry, finely divided matter, it is more particularly intended for automatically supplying measured quantities of comminuted soap to a washing machine such as is described in my co-pending application Serial No. 196,689, filed March 18, 1938, of which this application is a division.

In the ordinary washing cycle, a number of laundering materials are employed with the charges of water, some of these being customarily in liquid form, such as bluing, bleach and sour. Next to water itself, soap in one form or another is the most important substance used in washing fabrics. Soap may be supplied in liquid form by the use of either alcohol or heat, but liquid soap is expensive and open to various practical objections. According to the present invention, mechanism is provided for automatically and reliably supplying comminuted dry soap, that is, soap in the form of powder, granules or flakes.

It is an object of this invention to provide a mechanism which will be simple and rugged in structure and reliable in action.

An embodiment of the invention is hereinafter described, and is illustrated in the drawing of which

Figure 1 is a fragmentary plan view of mechanism embodying the invention.

Figure 2 is a section on the line 2—2 of Figure 1.

Figure 3 is a vertical sectional view of the mechanism shown in Figure 1, together with operating mechanism, on a larger scale.

Figure 4 is a fragmentary view similar to Figure 3, showing certain parts in different positions of operation.

Figure 5 is a fragmentary perspective view of a portion of the apparatus.

In the application hereinbefore referred to, a washing machine is described having a trough 300 in which laundering materials are supplied in measured quantities to the machine. The trough is preferably equipped with a suitable spray pipe 336 by which water is sprayed into the trough to wash the laundering materials along to the machine.

Above a portion of the trough 300 is mounted a mechanism for introducing predetermined quantities of soap into the trough as desired in carrying out a washing cycle. Such a mechanism may include a horizontal platform 220

on which slides a box 222 having an open top and bottom, the platform 220 serving as the bottom of the box. The platform is provided with a pair of side rails 224 between which the box 222 fits so that the box is guided thereby when it is moved along the platform 220. The upper surface of the platform 220 is preferably grooved as indicated in Figure 2, these grooves extending in a direction of motion of the box and forming a series of sharp parallel ridges 226 on which the box 222 rides. This prevents the formation of a packed film of soap on the surface of the platform 220. Although soap may pack in the grooves, the sharp ridges 226 remain clear. Since it has been found by experience that comminuted soap is liable to cake when heaped in a box, the box 222 is provided with a series of partition members 230 which are parallel to the end walls of the box and which form narrow transverse compartments 233 approximately three-fourths of an inch in width. For convenience in cleaning, the partition members 230 may be removably held in vertical slots 232 formed in the inside walls of the box 222. These partition members effectively prevent caking of powdered or granulated soap within the box. As indicated in Figure 3, the partition members 230 extend from points near the bottom of the box to about two-thirds of the way to the top of the box. Auxiliary partition members 234 may be employed to separate the successive batches of soap to be introduced into the washing machine, each batch filling a number of individual compartments.

In the platform 220 a transverse aperture 236 is provided, this aperture having a width somewhat greater than that of a narrow compartment 233. Mechanism is provided for imparting step-by-step movement to the box 222 so as to bring the several compartments 233 successively over the aperture 236. To this end, the box 222 may be provided with a series of tapering ratchet teeth 240 on one of its side walls (Figures 3 and 5), these teeth being engageable by a reciprocating pawl 242 and a detent 244 to prevent reverse movement of the box during advancing movement of the pawl 242. The pawl rests on the teeth 240 by its own weight. The detent 244 is pressed upward against the teeth by a counter-weight 245. As shown in Figure 3, the pawl may be connected to a rocking lever 246 which swings about the pivot 68. The lever 246 carries a cam roller 248 which rides on the edge of a cam 250 mounted on the constantly rotating shaft 24. As indicated in Figure 3, the shaft 250 is shaped so as to rock the arm 246 twice for each rotation

of the shaft 24, but it is obvious that the cam may be shaped to rock the lever any number of times for each revolution of the shaft. The roller 248 is held against the cam 250 by any convenient means such as a spring 252. Each time the shaft 24 makes half a revolution, the pawl 242 advances to the next tooth 240 and drags the box 222 along the platform 220 during the retracting movement of the pawl. Thus the compartments 233 are successively moved over the opening 236 so that their contents may fall through the opening.

Since two or more batches of soap are usually required for a complete washing cycle, it is desirable to supply all of the batches in the single box 222. The individual batches may be segregated by the auxiliary partition members 234 as shown in Figure 3. In order to stop the advancing movement of the box when the compartment 233 which immediately precedes one of the partition members 234 is moved over the aperture 236, a set screw 254 is inserted into a tooth 240 suitably related to the partition element 234. When the pawl 242 engages this tooth 240, a lug 256 engages the setscrew 254, so that, after the following retractive movement of the pawl which pulls the box along to a position in which the partition element 234 is at the edge of the opening 236, the pawl is held in retracted position by the lug 256 and the cam 250 thereupon revolves idly without moving the pawl. The pawl is thus held in an inoperative position until the time comes for the introduction of the next batch of soap into the washing machine. In order to accomplish this, the pawl 242 is lifted so as to move the lug 256 clear of the setscrew 254, thus permitting advancing movement of the pawl to engage the next successive tooth 240. Thereupon the cam 250 becomes effective to reciprocate the pawl 242 until the lug 256 engages the next setscrew 254.

Mechanism for releasing the pawl is illustrated in Figures 3 and 4 and consists of a cam member 260 mounted on the shaft 44. This cam has a series of high points 262 which successively engage a pin 266 mounted on a rocking arm 268. When the pin 266 rides up on one of the high points of the cam 260, as illustrated in Figure 4, the pin engages the under edge of the pawl 242 and raises the pawl so that the lug 256 clears the setscrew 254. The shaft 44 is soon advanced another step so as to lower the pin 266, permitting the lug 256 to engage the next setscrew 254 when it is reached as the box 222 is moved along the platform 220.

In using the herein described apparatus, the operator locates the box 222 in the position indicated in Figure 3 and fills it with a measured quantity of comminuted soap. The box is then ready to be operated by automatic control apparatus fully shown and described in my said application. The engagement of the lug 256 with a lug on the box holds the cam follower in an inactive position until the shaft 44 has been turned far enough to release the pawl 242. This occurs at those stages of a washing cycle when soap is needed in the washing machine. When the pawl 242 is released, it is automatically reciprocated until the lug 256 encounters the next setscrew 254. The feeding movement of the box 222 then stops until the lug 256 is again displaced by further rotation of the shaft 44. Suitable driving means for the shafts 24 and 44 are pro-

vided, as described and shown in my said application, the shaft 24 being constantly rotated while the shaft 44 is advanced at intervals step-by-step.

It is evident that various modifications and changes may be made in the embodiment of the invention herein shown and described without departing from the spirit or scope thereof as defined in the following claims.

I claim:

1. In a washing machine or the like, means for dispensing predetermined quantities of comminuted soap, said means comprising a platform having an aperture therethrough and parallel grooves in its upper surface defining ridges, a box having an open top and bottom riding on and movable along said ridges, a series of partitions in said box extending transversely with respect to said ridges and dividing the interior of the box into narrow compartments, and means for moving said box along said ridges to bring said compartments successively over said aperture.

2. In a washing machine or the like, means for dispensing predetermined quantities of comminuted soap, said means comprising an elongated platform having a transverse slot therethrough and side rails along its side edges, a box with open top and bottom fitted between said side rails to slide on said platform, a series of equally spaced upright transverse partition elements extending from the bottom of the box part way up toward the top to define a series of narrow transverse compartments in the lower portion of said box, extensions on selected partition elements dividing the upper portion of the box into large compartments, and means for imparting step-by-step movement to said box to bring said narrow compartments successively over said slot.

3. In a washing machine or the like, means for dispensing predetermined quantities of comminuted soap, said means comprising a platform having an aperture therethrough, a box having an open top and bottom slidably supported on said platform, a series of partitions in said box dividing the interior thereof into narrow compartments of substantially uniform width, means for guiding the movement of said box on said platform to bring said compartments successively over said aperture, ratchet teeth on said box, a reciprocable pawl engaging said teeth, and means for reciprocating said pawl through strokes equal to the width of one said compartment.

4. In a washing machine or the like, means for dispensing comminuted soap, said means comprising a platform having an aperture therethrough, a box with open top and bottom slidably supported on said platform, partition elements in said box dividing the interior into narrow compartments of substantially equal width, and driving means for imparting step-by-step movement to said box to bring said compartments successively over said aperture, said driving means including a series of ratchet teeth on said box spaced apart the width of a compartment, a reciprocable pawl adapted to engage said teeth in succession, spring pressing means pressing said pawl forward, cam means for retracting said pawl after each advance, and stop elements on said box engageable by said pawl to hold the pawl in retracted position.

LUCIEN PIERCE.
